BUILDING STRUCTURE

Edwin H. Piersen and John C. Anderson, Los Angeles, Calif., assignors to Unitype Engineering Company, Reno, Nev., a corporation of Nevada

Application December 6, 1933, Serial No. 701,187

22 Claims. (Cl. 189—1)

This invention relates to the structure of buildings generally but more particularly to those of one, two or three stories in height, having a solely metallic skeleton structure and intended for residential purposes, schools, clubs, etc.

Heretofore, opportunities for architectural diversification in buildings of this general class have been very limited; the structures did not have sufficient stability to withstand cyclone and 10 earthquake without damage; and the design thereof did not insure accuracy in fabrication nor provide expedient means for accomplishing a thickness of wall suitable to the varying requirements of usage and climate. Furthermore, the 15 high cost of such structures has barred extensive use thereof. Therefore, one object of this invention is to provide a wall frame which comprises a plurality of metallic structural units each having vertically, horizontally and/or diagonally disposed members of standard structural shapes 20 rigidly assembled in various combinations.

Another object is to provide a metallic structural wall unit having a minimum of weight and a maximum of strength.

Another object is to provide expedient and economical means for effecting a rigid bond between such a structural wall unit and an adjacent unit of like form.

Another object is to provide a metallic structural wall unit which comprises vertically disposed side members of such form and arrangement that when two of such units are rigidly joined edge to edge, the side member of one unit cooperates with the adjacent side member of the 35 other unit to form a structurally efficient column which will adequately support superimposed loads.

Another object is to provide means for anchoring such units to a cementitious or other foundation either directly or through the medium of 40 joists mounted thereon.

Another object is to provide a metallic structural wall unit which comprises a horizontally disposed member arranged as an integral part of the unit structure and located at or near the top thereof to serve as a unit spandrel beam extending from one of the "formed" columns to another, thereby providing an element integral with the unit structure on which floor joists and/or roof trusses may be supported and by 45 which the loads thereof may be transmitted to said "formed" columns, thus obviating any requirement for uniformity in spacing of the said columns and consequently enable spacing of 50 floor joists and roof trusses in the most economi-

cal manner regardless of the spacing of said columns.

Another object is to secure greater accuracy and uniformity in the measurements of such units and assure permanence in alignment of the 5 component parts thereof.

Another object is to provide a metallic structural unit comprising furring means adapted to accomplish any predetermined desired thickness 10 of wall.

Another object is to provide a metallic structural wall unit of this character which can be fabricated with utmost dispatch and at low cost 15 in a factory equipped with modern production facilities.

Another object is to provide such a metallic structural wall unit which will enable a wide range of diversification in architectural design.

These and other objects will be apparent from the following description and accompanying 20 drawings in which:

Fig. 1 is a general perspective view of a house structure embodying the primary elements of the invention.

Fig. 2 is an isometric view of a first-story structural wall unit suitable for a location in which a window is desired.

Fig. 3 is an isometric view of a first-story structural wall unit suitable for a location in which a door is desired.

Fig. 4 is an isometric view of a first-story structural wall unit suitable for a location where an opening is not required.

Fig. 5 is an isometric view of an upper story structural wall unit.

Fig. 6 is an isometric view of an assembly of wall units with floor and roof supporting joists or trusses.

Fig. 7 is an isometric view of a structural wall unit showing one form of furring means.

Fig. 8 is an isometric view of a structural wall unit showing another form of furring means.

Fig. 19 is a sectional view, taken on a line 15 19—19 of Fig. 17.

Fig. 20 is an elevation showing the means for anchoring the structural wall units to floor joists resting on a foundation.

Fig. 21 is a plan view of the same.

Fig. 22 is a sectional view, taken on a line 20 22—22 of Fig. 21.

20 In the drawings, the metallic structural wall unit of this invention is shown as comprising primarily vertically disposed side members 30, a horizontally disposed member 31, a horizontally disposed outside tie member 32 and inside tie member 33; secondarily, the said unit may also comprise one or more horizontally disposed members 34, one or more vertically disposed members 35 and a plurality of diagonally disposed members 36, the size and arrangement thereof depending upon the requirement for doors and windows or other openings in the wall structure as a whole. Each of the aforesaid members is proportioned and preferably positioned relative to the others so as to obtain a maximum of 25 strength and rigidity with a minimum of weight in the assembled unit and they are rigidly secured together by any suitable low-cost method, such as welding.

40 All of the members comprising the unit are preferably made of standard lightweight structural shapes. The side members 30 are preferably made of a channel section comprising a web portion 30a and flange portions 30b, the said member being positioned so that the web portion 45 extends preferably at right angles to the plane of the unit with the flange portions extending outwardly and parallel to the plane of the unit, thus constituting in effect a "half column" at each side of the unit. Member 31 is 50 preferably made of an I section comprising a web portion 31a and flange portions 31b or, if desired, it may be made of a T section, a channel section or it may be a truss. Member 32 may be merely a flat bar as shown and members 33, 34, 35 and 36 may be of angle section or otherwise in accordance with whatever shape would be most suitable in each instance.

60 In building a wall frame structure comprising such units, a plurality thereof, of suitable size and variety in design, are set up and assembled edge to edge, that is, with the member 30 of one unit in juxtaposition to the corresponding member of the adjacent unit and the said members are rigidly secured together by means of bonding devices hereinafter described.

65 When two of the said units are thus assembled in a common plane, the side members 30 thereof are joined together in any suitable manner that will accomplish a rigid bond, as by means of tie members 37 and tie bolt 38—each of said tie members partially shrouding the two "half columns" and said tie bolt extending therebetween as shown in Figs. 9, 10 and 11—whereupon the tie members 37 may be permanently secured to 70 both of the members 30 by welding or otherwise.

If desired, tie bolt 38 may thereafter be removed for similar utility elsewhere. Thus the two members 30 are combined to form a structurally efficient load-supporting column of square or box-like section which is thus built into the wall 5 structure thereby becoming an integral part thereof.

When two of the said units are assembled in relatively angular planes, a slightly different type of bonding device is required and this may 10 preferably comprise tie members 39 and 40 and tie bolt 41—shown in Figs. 13, 14 and 15—the said members being permanently secured to both of the members 30 by welding or otherwise and the tie bolt 41 being thereafter withdrawn if 15 desired. Here also a structurally efficient column effect is obtained and this is particularly so if the tie member 39 be made to extend substantially throughout the full height of members 30.

20 A wall structure comprising units of this character may be erected directly upon a cementitious or other similar foundation—as shown in Figs. 16, 17, 18 and 19—by provision of suitable means for anchoring the said units thereto. To that end 25 there is provided anchor bolts 42 inserted in the foundation, projecting upwardly therefrom and equipped with binding nuts 43. A base plate 44, comprising two vertically projecting studs 45 permanently affixed thereto and screw threaded for 30 binding nuts 46, is fitted freely over each of said anchor bolts and held securely upon the foundation 47 by the said nuts, all of the plates 44 being established at a uniform level by means of mortar or otherwise. The wall structure rests directly 35 upon the plates 44 with the columns positioned in line with the anchor bolts 42, thus the studs 45 are positioned between tie members 32 and 33, one on each side of each of said columns. Binding plates 48, fitting freely over studs 45 and under 40 nuts 46, serve to clamp the said tie members securely down upon plate 44 when the said nuts are drawn tight and thus the wall structure as a whole is securely anchored to the foundation.

When it is desired to have the wall structure 45 supported through the medium of joists resting upon the foundation—as shown in Figs. 20, 21 and 22—it is preferable to provide a sill member 49 extending in the plane of the wall and secured to the joists 50 in any suitable manner, preferably 50 by welding. The sill member 49 may be of any suitable shape but an angle section as shown is usually most advantageous. The wall structure is then erected upon said sill member and secured thereto in any suitable manner such as 55 bolts 51 extending upwardly through the horizontal web of the sill member, between tie members 32 and 33, and equipped with nuts 52. Binding plates 53, fitting freely on bolts 51 and under nuts 52, serve to clamp the said tie members 60 securely down upon the sill member 49 when the said nuts are drawn tight and thus the wall structure as a whole is securely anchored to the joists 50.

65 As clearly shown in Fig. 6, the horizontally disposed member 31 serves as a unit spandrel beam to support floor joists 54 or roof trusses 55 which rest thereupon and are permanently and rigidly secured thereto in any suitable manner such as by means of rivets or bolts but preferably by 70 welding. Thus the load of upper floors and roofs is transmitted to the columns formed by the side members 30. Many advantages result from this feature of the structural wall unit. For example:

(a)—The requirement for uniform spacing of 75

the column is obviated thus permitting of relatively wide variation in the widths of wall units and thereby satisfying any reasonable architectural desire.

5 (b)—Floor joists and roof trusses do not have to be uniformly or methodically spaced but they may be arranged in the most economical manner without regard to the location of doors or windows or other openings in the wall which affect 10 the spacing of the columns.

It will be understood that the structural wall unit of this invention extends substantially one story in height and when a structure of more than one story is erected, a series of units, similar 15 in general form, are used for each story—the units of the second story being superimposed upon those of the first story and units of the third story superimposed upon those of the second, thus constituting tiers of assembled units.

20 Anchoring the units of one story to the units of the story above and/or below it, if any, may be accomplished in various ways. For example:— As shown in Fig. 6, the members 30 of the superimposed unit may be spliced to the corresponding 25 members of the unit below by means of a bar 56 which is preferably positioned within the recess of the columns formed by the members 30 of adjacent units, as previously described, the said bar extending for a substantial distance 30 above and below the juncture of the said members, and the splice may be made effective by means of bolts 57 passing through the adjacent side members 30 and bar 56, or otherwise if desired. However a preferred form of splicing device is shown in Fig. 12. This form not only provides for splicing the superimposed unit to the unit below but it also serves as a bonding device by means of which sidewise adjacent units are joined together. As here shown, this combined 35 splicing and bonding device is very similar in character to the bonding device shown in Figs. 9, 10 and 11 and comprises tie-and-splice members 58 and tie bolts 59, each of said tie members partially shrouding the two "half columns" of the upper and lower units and extending for a substantial distance above and below the juncture thereof, and the tie bolts being spaced on each side of said juncture. Furthermore, when an 40 upper-story column is not positioned directly over the column in the next lower story but rests on the beam member 31, a combined bonding and anchoring device may be employed. A preferred form of such device is also shown in Fig. 12 and 45 comprises tie-and-anchor members 60 and tie bolt 61, said members partially shrouding the two "half columns" of the upper-story units and being provided with portions 60a which underlie the flange portion 31b of member 31 and effect contact with the underside of said flange portion 50 thus serving to anchor the upper-story unit to the beam member of the lower unit. As in the case of the bonding device shown in Figs. 9, 10 and 11, the members 58 and 60 are permanently secured to the "half columns" and to the beam member 31 by welding or otherwise and the tie bolts 59 and 61 may thereafter be removed if desired.

In order to provide vertical clearance between member 31 and members 32 and 33 for the floor beams of upper stories, the side members 30 of the upper-story units have a portion 30c which extends below members 32 and 33, as shown in detail in Fig. 5. With this exception, upper-story units may be substantially the same in all 70 general respects as those of the first story.

In conjunction with a wall frame comprising metallic structural units, as herein described, the invention comprises furring means for accomplishing any desired thickness of wall. Such means may take various forms, but, as shown in 5 Figs. 7 and 8, it embodies primarily vertically disposed metallic members 62 or 63 which may be of any suitable light-weight structural form but preferably of channel section, as shown.

Under certain conditions, wherein it is desired 10 to have a thickness of wall not greatly in excess of that of the wall unit structure, the furring members, such as 62, may be attached directly to the members of the said structure (as shown in Fig. 7) and secured thereto in any suitable 15 manner but preferably by welding and, in such instances, the breadth of the channel section determines or controls primarily the thickness of the finished wall.

However, when it is desired to have a much 20 greater thickness of wall than that of the wall unit structure, the furring members, such as 63, may be spaced from the said unit structure (as shown in Fig. 8) preferably by means of lateral horizontal members 64, attached to some of the 25 members comprising the said unit structure, and longitudinal horizontal members 65 attached to the members 64, both of which may be of any suitable lightweight structural form but preferably of channel section as shown. Members 63, 30 64 and 65 may be rigidly secured one to the other and member 64 securely anchored to the unit structure by means of clips, wires or other suitable means but preferably by welding each junction in the assemblage so as to obtain rigidity 35 and strength in the whole framework. It will be apparent that the length of members 64 is the major factor in controlling the thickness of the finished wall.

With either of these furring arrangements, the 40 members 62 or 63 serve as the structural mounting for metallic lath, wire mesh or other plaster base which may be attached thereto by any suitable means, and upon this base the exterior stucco or veneer and the interior plaster may be applied 45 thus making a completed wall having the desired thickness. Or, if desired, plasterboard, or other insulating material may be attached directly to the structure of the wall units in lieu of the furring and metal lath as a base for the plaster 50 finish, or such materials may be left in their natural state and suitably decorated.

From the foregoing it will be apparent that we have thus provided a wall structure for buildings which accomplishes the objectives herein 55 set forth and described, and it will be understood that the details of design and construction disclosed are to be considered as merely illustrative of the invention and not in a limiting sense.

Having thus fully described our invention, 60 what we claim as new and desire to secure by Letters Patent, is:

1. A wall frame comprising a plurality of metallic structural units, each of said units having vertically disposed side members, a horizontally disposed top member extending from one of said side members to the other, rigidly secured thereto and adapted to serve as a support for floors and roofs, transmitting the loads thereof to said side members, and two horizontally disposed bottom members spaced apart and extending from one of said side members to the other, rigidly secured thereto and spaced from the lower end thereof when said unit is applied to an upper story of a building. 70 75

2. A wall frame comprising a plurality of metallic structural units arranged relatively edgewise horizontally and in tiers, each of said units having vertically disposed side members of channel section arranged with the side walls of said channel extending parallel to the plane of said unit and projecting outwardly so as to establish a hollow column as an integral element of said wall frame at each juncture of two units 5 when the same are arranged adjacent edgewise and the respectively adjacent side members thereof are rigidly joined one to the other, and a splice member positioned within the hollow of said column and extending above and below the 10 juncture of said tiers, said splice member being rigidly secured to the adjacent side members of the units in one tier and the corresponding side members of the units in the adjacent tier.
3. A wall frame comprising a plurality of metallic structural units, each of said units having vertically disposed side members of such form and so positioned therein as to effect a hollow-column structure when two of said units are arranged adjacent and secured sidewise, one to 15 the other, a horizontally disposed top member extending from one of said side members to the other, rigidly secured thereto and adapted to serve as a support for floors and roofs, transmitting the loads thereof to said hollow-column 20 structure, and two horizontally disposed bottom members spaced apart and extending from one of said side members to the other, rigidly secured thereto and spaced from the lower end thereof when said unit is applied to an upper 25 story of a building.
4. In a wall frame comprising a plurality of metallic structural units arranged relatively edgewise horizontally and each having vertically disposed side members of channel section arranged with the channel facing outwardly, a device adapted to engage the respectively adjacent side members of adjacent units on opposite sides of said channel and rigidly unite one unit to the other, said device comprising, in combination, two duplicate elements having the form of a channel and disposed so as to embrace said 30 respectively adjacent side members and hold the same in fixed relation one to the other and a third element adapted to bind said other elements into engagement with said side members, thus creating a hollow column which becomes an integral element of the wall frame at each juncture of two units.
5. In a wall frame comprising a plurality of metallic structural units arranged edge to edge horizontally and spaced slightly apart, said units having vertically disposed side members of channel section arranged with the channel facing outwardly, a device adapted to engage the respectively adjacent side members of adjacent units on opposite sides of said channel and rigidly unite one unit to the other, said device comprising, in combination, two duplicate elements having the form of a channel and disposed so as to embrace said 35 respectively adjacent side members of adjacent units and hold the same spaced apart and in fixed relation one to the other, said elements having an aperture coinciding with the space between said units, and a tension member extending through said apertures and between said units and adapted to bind said elements into engagement with said side members, thus creating a hollow column which becomes an integral element of the wall frame at each juncture of two units.
6. In conjunction with a wall frame comprising a plurality of metallic structural units having vertically disposed side members of channel section arranged with the channels facing outwardly so as to constitute a hollow column structure when two units are united edge to edge, said units also having two horizontally disposed bottom members spaced apart and extending from one of said side members to the other and rigidly secured thereto, means for anchoring said wall frame directly to a cementitious foundation, said means comprising in combination, a base plate, means to secure said plate to said foundation, said plate having two upwardly extending projections formed integral therewith and spaced apart a 15 distance greater than the width of said column, and binding means associated with each of said projections whereby the wall frame may be imposed upon said base plate with said projections disposed between said bottom members, one on each side of said column, and said binding means applied to secure said bottom members to said plate and therethrough secure the wall frame structure to said foundation.
7. In conjunction with a wall frame comprising a plurality of metallic structural units having vertically disposed side members of channel section arranged with the channels facing outwardly so as to constitute a hollow column structure when two units are united edge to edge, said units also having two horizontally disposed bottom members spaced apart and extending from one of said side members to the other and rigidly secured thereto, means for anchoring said wall frame to a foundation structure comprising a plurality of joists and a sill member imposed thereon and rigidly secured thereto, said means comprising, in combination, a plate member, and binding means associated with said plate member and said sill member and disposed between said bottom members, whereby the wall frame may be imposed upon said sill member and said plate member imposed upon said bottom members, one on each side of said column, and said binding means applied to secure said bottom members to said sill member thereby anchoring the wall frame to said foundation structure.
8. In conjunction with a wall frame comprising a plurality of metallic structural units rigidly united edgewise, means for anchoring said structural units, directly to a cementitious foundation, which consists in the provision of a base plate having a plurality of projections formed integral therewith, means to secure said plate to the foundation, and binding means associated with said projections spaced from said plate and adapted to engage the structure of the wall frame units whereby the said frame may be securely attached to said plate.
9. In conjunction with a wall frame comprising a plurality of metallic structural units rigidly united edgewise, means for anchoring said structural units to a foundation structure comprising a plurality of joists and a sill member imposed thereon and rigidly secured thereto, which consists in the provision of a plate member adapted to engage the structure of the wall frame units at a point spaced above said sill member, and binding means associated with said plate member and the sill member whereby the wall frame may be securely attached to the sill member.
10. In conjunction with a wall frame consisting of a plurality of metallic structural units, furring means comprising an assemblage of me-

tallic members rigidly secured one to the other, the inner members of said assemblage being horizontally disposed at right angles to the plane of said units and securely attached to the metallic structure thereof, and the outermost members of said assemblage being vertically disposed and adapted to support a plaster base in a plane spaced from the plane of said units but parallel therewith, the length of said inner member being the major factor in establishing the extent of the space between said planes and thereby a predetermined thickness of the finished wall may be predicated primarily upon the length of said inner members.

15. 11. A wall unit comprising a plurality of metallic members arranged in a common plane and rigidly assembled to form a unitary structure, two of said members having a rib-like form and being disposed vertically, one at each side of said structure, with the plane of ribbed portions thereof extending parallel to the plane of the unit, the other members of said unit being variously disposed, some horizontally and others diagonally, between said vertical members and arranged relative thereto so as to reinforce the same and thereby assure rigidity and permanency in alignment of said structure as a whole.

12. A wall frame comprising a plurality of metallic structural units arranged relatively edgewise horizontally and in tiers, each of said units having vertically ribbed side members adapted to cooperate with the respective side members of edgewise adjacent units to form a ribbed column as an integral element of the wall frame at each juncture of two units, and a device arranged to extend above and below the juncture of said tiers and adapted to engage the cooperating side members of the units in one tier and the corresponding side members of the units in the adjacent tier whereby said column is made continuous throughout the several tiers.

13. A wall frame comprising a plurality of metallic structural units arranged relatively edgewise horizontally and in tiers, each of said units having vertically ribbed side members adapted to cooperate with the respective side members of edgewise adjacent units to form a ribbed column as an integral element of the wall frame at each juncture of two units, and a combined bonding and splicing device associated with the cooperating side members in one tier and the corresponding side members in the adjacent tier so that each pair of cooperating side members are bound together and said tiers are spliced one to the other whereby said column is made continuous throughout the several tiers.

14. A wall frame comprising a plurality of metallic structural units arranged relatively edgewise horizontally and in tiers, each of said units having vertically ribbed side members adapted to cooperate with the respective side members of edgewise adjacent units to form a ribbed column, as an integral element of the wall frame at each juncture of two units, each of said units also having a horizontally disposed member extending from one side member to the other at the top thereof, said member being formed and arranged so as to constitute a spandrel beam, integral with the unit structure, for transmitting loads imposed thereupon to the respective side members, and a combined bonding and anchoring device associated with the cooperating side members and the spandrel beam member therebelow whereby, when said side members are superimposed upon said beam member, said side

members are bound together and anchored to said beam member.

15. A wall frame comprising a plurality of metallic structural units arranged relatively edgewise, each of said units having vertically disposed side members and a top member extending from one of said side members to the other and rigidly secured thereto, thus becoming an integral part of said unit, said top member having a cross-sectional form analogous to a standard structural girder suitable for service as a spandrel beam whereby the loads of floors and roofs imposed upon each unit intermediate the side members will be transmitted to the respective side members, each of said units also having two horizontally disposed bottom members extending from one of said side members to the other, rigidly secured thereto, and arranged with their lower faces flush with the lower ends of said side members, said bottom members being spaced apart thus providing for the application of a binding device extending therebetween and bearing against the upper face of each of said bottom members whereby each unit may be securely anchored to a foundation or sill structure when said unit is applied to the first story of a building.

16. A wall frame comprising a plurality of metallic structural units arranged relatively edgewise, each of said units having vertically disposed side members formed and arranged so as to accomplish per se a structurally efficient load-supporting column of box-like section as a constituent element of said wall frame at each juncture of two units when the same are arranged adjacent edgewise and the respectively adjacent side members thereof are rigidly joined one to the other, each of said units also having a top member extending from one of said side members to the other and rigidly secured thereto, thus becoming an integral part of said unit, said top member having a cross-sectional form analogous to a standard structural girder suitable for service as a spandrel beam whereby the loads of floors and roofs imposed upon each unit intermediate the side members will be transmitted to the respective columns, each of said units also having two horizontally disposed bottom members extending from one of said side members to the other, rigidly secured thereto and arranged with their lower faces flush with the lower ends of said side members, said bottom members being spaced apart thus providing for the application of a binding device extending therebetween and bearing against the upper face of each of said bottom members whereby each unit may be securely anchored to a foundation or sill structure when said unit is applied to the first story of a building, and metallic means to rigidly unite said respectively adjacent side members.

17. In conjunction with a wall frame consisting of a plurality of metallic structural units, furring means comprising a plurality of elongated members disposed in a vertical plane lying parallel with the plane of said wall frame but spaced therefrom, and spacing means comprising a plurality of elongated members secured to said units and extending longitudinally at right angles to the plane thereof whereby the length of said last mentioned members constitutes the major factor in the thickness of the finished wall.

18. A structural unit comprising a rigid assemblage of elongated metallic members arranged so as to constitute a frame suitable for load-bearing service when united edgewise with similar units in the formation of a wall, two of said members

constituting the vertical side members of said frame and being formed so as to provide columnar elements within the unit structure for supporting loads superimposed upon said frame, another of 5 said members constituting the top member of said frame and being formed so as to provide a spandrel beam within the unit structure which will transmit to said columnar elements the loads imposed upon said frame intermediate said side members, and two other of said members constituting the bottom members of said frame, said bottom members being relatively spaced horizontally thus providing for the application of a binding device extending therebetween and bearing 10 against the top face of each of said bottom members whereby said frame may be secured to a supporting structure.

19. A structural unit comprising a rigid assemblage of elongated metallic members arranged so 20 as to constitute a frame suitable for load-bearing service when united edgewise with similar units in the formation of a wall, two of said members constituting the vertical side members of said frame and being formed so as to provide columnar 25 elements within the unit structure for supporting loads superimposed upon said frame, another of said members constituting the top member of said frame and being formed so as to provide a spandrel beam within the unit structure which will transmit to said columnar elements the loads imposed upon said unit intermediate said side members, two other of said members constituting the bottom members of said frame, said bottom members being relatively spaced horizontally thus 30 providing for the application of a binding device extending therebetween and bearing against the top face of each of said bottom members whereby said frame may be secured to a supporting structure, and others of said members being disposed 35 within said frame and arranged so as to provide for an opening through said wall.

20. A structural unit comprising a rigid assemblage of elongated metallic members arranged so as to constitute a frame suitable for load-bearing service when united edgewise with similar units in the formation of a wall, two of 40 said members constituting the vertical side members of said frame, each side member being formed as a channel and arranged with the channel side walls extending outwardly parallel to the plane of the unit so as to constitute one-half of a box-like column and thus provide columnar elements within the unit structure for supporting loads superimposed upon said frame, another of said members constituting the top member of said frame and being formed so as to provide a spandrel beam within the unit structure which will transmit to said columnar ele- 45

ments the loads imposed upon said unit intermediate said side members, another of said members constituting a bottom member of said frame, others of said members being disposed within said frame and arranged so as to provide for an opening through said wall, and still others of said members being arranged to extend diagonally from one of said side members to one of 5 said last mentioned members so as to reinforce said side member against horizontal flexure thus 10 obtaining extraordinary rigidity of said frame and enabling said side member to better support the load transmitted thereto by said spandrel beam.

21. In a wall frame comprising a plurality of metallic structural units, two of said units being arranged adjacent edgewise and disposed in relatively angular vertical planes, each of said units having vertically disposed side members of channel section arranged with the channel facing outwardly, a device adapted to engage the respectively adjacent side members of the said two units and rigidly unite one of the said two units to the other, said device comprising, in combination, two channel-embracing elements adapted to embrace respectively adjacent side members and hold the same in fixed relation one to the other, and a third element adapted to bind said other elements into engagement with said side members, thus creating a structurally efficient column of an approximately angular section which becomes an integral element of the wall frame at a corner juncture thereof.

22. In a wall frame comprising a plurality of metallic structural units, two of said units being arranged adjacent edgewise but spaced slightly apart and disposed in relatively angular vertical planes, each of said units having vertically disposed side members of channel section arranged with the channel facing outwardly, a device adapted to engage the respectively adjacent side members of the said two units and rigidly unite one of the said two units to the other, said device comprising, in combination, two channel-embracing elements adapted to embrace said respectively adjacent side members and hold the same spaced apart and in fixed relation one to the other, said elements having an aperture coinciding with the space between said units, and a tension member extending through said apertures and between said units and adapted to bind said two elements into engagement with said side members, thus creating a structurally efficient column of an approximately angular section which becomes an integral element of the wall frame at a corner juncture thereof.
